UNITED STATES PATENT OFFICE.

PHILIPP WEIGAND AND PHILIP SCHUH, OF WEST CHESTER, NEW YORK.

IMPROVEMENT IN BOYS' SLEDS.

Specification forming part of Letters Patent No. 179,832, dated July 11, 1876; application filed May 13, 1876.

To all whom it may concern:

Be it known that we, PHILIPP WEIGAND and PHILIP SCHUH, both of West Chester, in the county of Westchester and State of New York, have invented certain new and useful Improvements in Sleds; and we do hereby declare that the following is a full, clear, and exact description of the same, reference being had to the accompanying drawing, which forms part of this specification.

This invention relates to what are known as "boys' sleighs or sleds;" and consists in certain novel constructions and combinations of parts, including a turning and reversible guide-runner, provided with a circular track-bearing for its frame and a steering-wheel on the under side of the seat, also with an anchor-brake applied to said runner-frame, and controlled by a lever and spring slide or stop fitted to engage in an adjustable manner with the guide-runner frame, all substantially as hereinafter more fully described.

In the accompanying drawing, Figure 1 represents a side view of the sled with the guide-runner adjusted for travel in the direction indicated by arrow in said figure; Fig. 2, a similar view of the same with the guide-runner reversed for travel in a reverse direction without turning the sled, as indicated by arrow in such figure. Fig. 3 is a partly-broken inverted plan or under view of the sled with the guide-runner in the position represented in Fig. 1. Fig. 4 is a mainly central vertical longitudinal section through the guide-runner portion of the sled, and Fig. 5 a vertical transverse section in part, mainly on the line $x-x$. These two last figures are upon a somewhat larger scale than the other figures of the drawing.

A is the seat of the sled, and B B its main runners, which are turned up or bowed at both of their ends. These runners occupy side positions toward the one end of the seat. C is the guide-runner, occupying a centrally-longitudinal position under the seat at its opposite end, and D the frame of said runner. E is the steering-wheel, carried by said guiding-runner or its frame, and occupying a horizontal position under the seat, beyond either side or edge of which it projects, to enable the rider or operator to take hold of said wheel, and,

by turning the latter, to turn the guide-runner, and so steer the sled; also whereby the guide-runner may be turned to occupy reverse positions, as shown in Figs. 1 and 2.

Instead of suspending the guide-runner and its frame to turn on a king-bolt, which is liable to get loose, and but imperfectly sustains the guide-runner against the various strains to which it is subjected, it is suspended on and fitted to travel around a circular track-bearing, G, on the under side of the seat A. This bearing may consist of an upper flat metal annular plate or ring, b, secured to the under side of the seat A, and a smaller under similar flat ring, e, arranged concentrically below the ring b, and secured to said seat; also an interposed disk or circular guiding-piece, d, likewise fast to the under side of the seat A. These several parts are so proportioned and arranged as to provide for the free circular travel or run of a flat circular plate or ring, e, between the fast rings b c, and against or around the guiding-disk d, said ring e being fast on or forming part of the guide-runner frame D. This mode of suspending the guide-runner or its frame provides for its steady and easy adjustment around an imaginary center, which is the center of the track-bearing G.

H is an anchor-brake, hinged at its upper end to a horizontal bar or lever, I, carried by the guide-frame D, and extending across the latter, with its one end playing in a fulcrum seat or bearing, f, and its opposite end being free to travel about or around a curved slotted guard or plate, h, fast to the frame D. This lever I is also made capable of movement in direction of its length, and is constructed to constitute, in addition, a spring stop or lock by means of a spring, i, applied to its fulcrum end, and a hook or bolt, l, on its opposite end, which hook, by pulling laterally outward on the lever I at its bolt end, which is accessible from within the steering-wheel E outside of the seat A, becomes disengaged from any one of a series of notches or holes, m m, in the guard h. This permits of the lever I being swung horizontally to raise or lower the anchor-brake H, so as either to draw it wholly within the guide-runner C, through which it projects, or to give it any desired degree of

anchoring projection below said runner. By releasing outward pull or draft on the lever *I* its bolt or hook *l* is shot by the action of the spring *i* into lock with one or other of the holes *m*, and so made to hold the anchor-brake at the adjustment given it by the vibration of the lever *I*, which latter is provided with a head or handle, *n*, to facilitate the operation of the lever from within the rim of the steering-wheel by the rider of the sled, and which he may do, if desired, without releasing his hold of the steering-wheel.

The operation may be briefly described as follows: Supposing a boy to be sitting on the seat *A* over the guide-runner frame, with the guide-runner *C* turned to occupy the position represented for it in Fig. 2, or supposing the boy to be lying on the seat, with the guide-runner turned to occupy the position shown for it in Fig. 1, and the sled to be going down hill, said boy or operator tightly grasps or holds the steering-wheel *E* with his hands, and firmly retains himself on the sled by such hold or grasp, and steers the sled in any desired direction at the same time. If necessary to check the speed or stop the sled altogether, he grasps the handle *n* with his fingers, without, if desired, letting go of the steering-wheel, and pulls on the lever *I* to disengage the bolt *l*, and turns said lever till the anchor-brake *H* enters the frozen or other surface being traveled over, and, on releasing hold of the handle *n*, the anchor-brake becomes locked in its adjusted position. The

anchor-brake *H* is of a sharp hook-shaped construction at its entering end, and its suspension is such that, when liberated and adjusted to enter the ground, the motion of the sled serves to draw it into the latter, and the superincumbent weight holds it there till purposely released by the rider of the sled.

The sled may be drawn over the ground, when required, by a cord or rope attached to a ring, *S*, on the forward end of the guide-runner.

We claim—

1. The combination, with the seat *A* and main runners *B* *B*, having both of their ends turned up or bowed, of the reversible guide-runner *C*, with its attached steering-wheel *E*, substantially as specified.

2. The reversible guide-runner *C*, with its frame *D* and attached steering-wheel *E*, arranged in relation with the seat *A*, in combination with the circular track-bearing *G*, on which the guide-runner frame rests, essentially as described.

3. The combination of the anchor-brake *H*, and its operating-lever and spring-stop *I*, *i*, *h*, and *l*, with the steering-wheel *E*, the guide-runner *C*, and the seat *A*, substantially as specified.

PHILIPP WEIGAND.
PHILIP SCHUH.
